FIG. 5.

INVENTOR.

SAMUEL ROBERT RAMSAY
BY *Wm. W. L. Co.*
ATTORNEYS.

UNITED STATES PATENT OFFICE

SAMUEL ROBERT RAMSAY, OF SANTA CRUZ, CALIFORNIA

DOOR SEAL

Application filed October 7, 1929. Serial No. 398,048.

The present invention relates to improvements in door seals, and its principal object is to provide a seal for the bottom of a door for preventing draft from passing through the opening below the door.

In building construction as practiced at the present time, it is customary to leave considerable space between the bottom of the door and the floor so as to allow the door to clear a rug or carpet lying in the adjacent room when the door is opened.

It is the object of the present invention to provide a sealing means or draft strip in connection with a door that will move into active position so as to furnish an effective seal when the door is closed and that will move automatically into inactive position for allowing the door to clear a rug when the door is opened.

It is further proposed in connection with the present invention to provide means for moving the strip one way or the other that will become active automatically upon the opening or closing of the door.

Further objects and advantages of my invention will appear as the specification proceeds.

The preferred form of my invention is illustrated in the accompanying drawing, in which

Figure 1 shows a door in closed position with my sealing strip attached thereto,

Figure 2 a horizontal section taken along line 2-2 of Figure 1,

Figure 3 a view of the door in open position,

Figure 4 a vertical fragmentary section taken along line 4-4 of Figure 1, and

Figure 5 an enlarged detail view of a mounting means for a spring used in my device.

While I have shown only the preferred form of the invention, I wish to have it understood that various changes or modifications may be made within the scope of the claims hereto attached without departing from the spirit of the invention.

Referring to the drawings in detail, my invention is illustrated in connection with a door 1 hingedly secured as at 2 to the door

frame 3, suitable stops 4 being provided in the conventional manner against which the door rests when held in closed position. The door may swing from the full-line position shown in Figure 2 into the dotted-line position shown in dotted lines in the same figure.

My invention more particularly comprises a sealing strip 5 of suitable width and thickness and of a length corresponding substantially to the width of the door opening as defined by the two stops 4. This sealing strip is preferably provided with a groove 6 in its bottom adapted to receive a strip of felt or similar material indicated at 7.

The sealing strip is supported relative to the door by means of two springs 8, each comprising a vertical member 9 held in a clip 10 fastened to the face of the door by means of screws 11 and an arm 12 extending downward in a slanting direction, the arm being offset as shown at 13 to clear the strip 5 and being bent at its extreme end as shown at 14. The latter end is received in a socket 15 embedded in the surface of the sealing strip. The lower end of the vertical member 9 is preferably bent at right angles and is received in a socket 16 in the clip 10 for preventing turning and rising movements of the vertical member 9 of the spring.

The tension of the two springs is such as to normally hold the sealing strip in inactive position, that is, flush with the bottom of the door so that the latter may clear a rug or carpet and also substantially flush with the inner or hinged edge of the door as shown in Figure 3. As the door is closed, the inner end of the strip strikes the stop 4 and the strip is moved forward along the face of the door toward the outer edge and into a midway position. This outward movement of the strip is accompanied by a downward movement due to the action of the spring arms 8, and this downward movement is sufficient to bring the bottom of the strip of felt 7 into contact with the floor so that a perfect seal is obtained.

When the door is opened, the spring arms 8 automatically move the strip toward the inner edge of the door, and this movement is accompanied by a rising of the strip which

causes the latter to clear any rug or carpet that would normally be cleared by the door.

It should be understood that the springs 8 may be made in many different forms as 5 long as they perform the essential function of moving the strip inwardly when the door is opened and of at the same time raising the strip into inactive position while allowing the strip to return to an active position under 10 the impact of the closing door.

It should be further understood that while 15 in the drawing my sealing strip is shown as applied to the face of the door, it might as well be accommodated in a slot in the bottom of the door if it is desired to conceal the working mechanism.

I claim:

1. In combination, a swingable supporting member, a sealing strip and spring means 20 holding the strip to the member with freedom of swinging motion between sealing and non-sealing positions, the said spring means being made to also urge the sealing strip toward the face of the member.

2. In combination, a swingable supporting member, a sealing strip and spring means holding the strip to the member with freedom of swinging motion between sealing and non-sealing positions, the spring means bearing on 30 the face of the strip for urging the strip toward the supporting member.

3. In combination, a door, a sealing strip and spring means holding the strip to the door with freedom of swinging motion between sealing and non-sealing positions, the said spring means being made to urge the sealing strip toward the face of the door.

4. In combination, a swingable supporting member, a sealing strip and spring means holding the strip to the member with freedom of swinging motion between sealing and non-sealing positions, the spring means comprising a spring wire having a vertical section adapted for fastening to the supporting member, an intermediate section extending from the upper end of the vertical section in a downwardly slanting direction over the sealing strip and a horizontal end section adapted to be received in a socket in the strip.

5. In combination, a swingable supporting member, a sealing strip and spring means holding the strip to the member with freedom of swinging motion between sealing and non-sealing positions, the spring means comprising a spring wire having a vertical section adapted for fastening to the supporting member, an intermediate section extending from the upper end of the vertical section in a downwardly slanting direction over the sealing strip and a horizontal end section adapted to be received in a socket in the strip, the vertical section terminating in a transverse finger having means for holding the same to the face of the supporting member.

6. A wire spring of the character described comprising a vertical section having a horizontal finger at its lower end, an intermediate section extending from the upper end of the vertical section in a downwardly slanting position, and a horizontal end section running at right angles to the finger.

SAMUEL ROBERT RAMSAY.
